Primary Examiner — George D Kirschbaum*Assistant Examiner* — Jennifer Watkins(74) *Attorney, Agent, or Firm* — Kutak Rock LLP; Bryan P. Stanley(57) **CLAIM**

The ornamental design for a support brace, as shown and described.

DESCRIPTION

FIG. 1 is a front perspective view of a support brace of the instant invention, shown in a position of use on a human shin.

FIG. 2 is a side perspective view of the support brace of FIG. 1, shown in a position of use on a human elbow.

FIG. 3 is a front view of the brace of FIG. 1.

FIG. 4 is a rear view of the brace of FIG. 1.

FIG. 5 is a left side view of the brace of FIG. 1.

FIG. 6 is a bottom view of the brace of FIG. 1.

FIG. 7 is a top view of the brace of FIG. 1; and,

FIG. 8 is a right side view of the brace of FIG. 1.

The broken lines showing a person's leg and arm are for the purpose of illustrating environment and form no part of the claim.
